DESIGN FOR A WATCHCASE OR SIMILAR ARTICLE

Fulco di Verdura, New York, N. Y., assignor to Paul E. Flato, New York, N. Y.

Application November 27, 1937, Serial No. 73,220

Term of patent 3½ years

To all whom it may concern:

Be it known that Fulco di Verdura, a citizen of Italy and resident of New York city, in the county of New York and State of New York, has invented a new, original, and ornamental Design for a Watchcase or Similar Article, of which the following is a specification, reference being had to the accompanying drawing, forming part thereof, in which,

Fig. 1 is a plan view of a watchcase embodying my design, showing the same in closed position.

Fig. 2 is a bottom view thereof.

Fig. 3 is an end view thereof.

Fig. 4 is a plan view, showing my envelope watchcase in open position; and

Fig. 5 is an end view thereof.

I claim:

The ornamental design for a watchcase or similar article, substantially as shown.

FULCO DI VERDURA.
